SHOESHINE KIT

Harold H. Deems, Sheridan, Wyo.

Application March 28, 1938, Serial No. 198,608

1 Claim. (Cl. 15—258)

The invention relates to an accessory kit and more especially to a shoe shine kit.

The primary object of the invention is the provision of a kit of this character, wherein a case is constructed to afford storage of accessories, those used for shining or polishing shoes, and when open assures easy access to the accessories and also when closed will retain the accessories in an orderly manner.

Another object of the invention is the provision of a kit of this character, wherein the case for the carrying of the accessories is of a construction for enabling the carrying thereof and the holding of the accessories in a compact manner handy for use.

A further object of the invention is the provision of a kit of this character, wherein the case for the accessories affords tray sections, these being arranged for receiving selected accessories for the storage thereof in a compact manner.

A still further object of the invention is the provision of a kit of this character, which is simple in construction, thoroughly reliable and effective in operation, neat in appearance, assured of compactness both in the case construction and in the assembly of the accessories to be held therein, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

35 In the accompanying drawing:

Figure 1 is a plan view of the kit constructed in accordance with the invention and in open position.

Figure 2 is a vertical longitudinal sectional view showing the kit partly folded.

Figure 3 is a vertical transverse sectional view through the kit when folded.

Figure 4 is a fragmentary side elevation partly in section showing in detail a dauber and its handle constituting one of the articles of the accessories stored within the kit and ready for use.

Figure 5 is a bottom plan view of the dauber handle with the dauber proper removed.

Figure 6 is a fragmentary detail elevation showing the separation of the cover for a can adapted to hold polishing composition, being another of the articles of the accessories within the kit.

Similar reference characters indicate corre-

sponding parts throughout the several views in the drawing.

Referring to the drawing in detail, A designates generally a case for containing accessories used in shoe polishing or shining and includes opening and closing body sections 10 and 11, respectively, these being in the form of trays providing compartments 12 and such sections are joined in the creation of the case A through the medium of a flexible back 13 functioning as a hinge connection between said sections. The sections 10 and 11 are of substantially rectangular form and match with each other on the closing of the case. The meeting sides of the sections 10 and 11 on the closing of the case A are fully open and the wall edges at the open sides of said sections, that is, the side walls and one end wall of each, have fast thereto a zipper fastener carrying tape 14 with the zipper fastener 15 a part thereof, the said zipper fastener being of the familiar 10 slideable closure type and includes a closure runner 16, hand operated. This fastener, on the bringing together of the sections 10 and 11, enables the fastening of the case A in closed condition and when the sections 10 and 11 of the latter are unfastened, such sections can be spread in an open position with the tray formations disposed in the same plane with each other and opening upwardly for easy access thereto.

In the section 10 is received the boxes or cans 17 containing blackening or polishing compositions, these being conventional and are held removable from the compartment 12 constituted in the section 10 by a retaining strap 18. This compartment 12 in the section 10 is to contain 20 a pair of daubers 20, these being releasably held 25 orderly therein in any suitable manner.

Within the compartment 12 in the section 11 is adapted to be held a polisher involving a block-like back 21 carrying at one face thereof a padded 40 polishing medium 22, being fixed to the back in any suitable manner. The back 21 at its opposite ends 23 is releasably engageable in retaining loops or straps 24 built within the compartment 12 in the section 11 and in this manner 45 the said polisher is retained therein.

The back 21 of the polisher is provided with a recess 25 longitudinally disposed and opening through one longer edge thereof for the accommodation of a handle 26 for each dauber 20. 50 This handle 26 at one end is formed with a head 27 provided with a jaw 28 and a spring clip 29, respectively, these releasably fastening the dauber 20 with the head for the use of the handle 26 therewith.

Each box or can 17 is provided with a releasable cover 30, the box and cover being tongue and grooved at 31 and 32, respectively, for the interlocking of the cover 30 with said box on the closing of the latter.

The jaw 28 and clip 29 on the head 27 allow the separable fastening of either dauber 20 with the head for interchangeable use of the daubers for shining shoes, each dauber being used in the usual manner and similarly the polisher in the shining of shoes.

The kit, when the case A is closed and fastened in this condition, will be compact and of a size for the convenient storage thereof or the carrying of the same upon the person.

The back 13 between the sections 10 and 11 of the case A closes the compartments 12 thereof at the other ends remote from the free ends of said sections to give tray formation effect to these sections when the case A is in open position and these tray-like formations can be disposed in the same plane with each other when the said case is fully open when the latter is resting on a stand or support.

The compartment 12 in the section 11 snugly accommodates the polisher and one of the walls of said section closes the pocket constituted by the recess 25 for receiving the handle 26 so that the latter will be held within the polisher when the latter has its snug fitting in the section 11 and on the closing of the case the pad 22 effecting the polishing medium for the polisher will bear upon the boxes 17 within the compartment formed by the section 10 and thus hold these

orderly within said section as well as retaining the lids 30 fastened in place.

The side walls of the sections 10 and 11, when in open position, are freely flexible so as to permit easy and convenient removal of the parts held within the tray-like compartments 12 of the case.

The loops or straps 24 engaged about the ends of the back 21 of the polisher eliminate any lateral displacement of the polisher and releasably fix it within the section 11.

The boxes or cans 17 are preferably of a diameter for snug fitting in the compartment 12 in the section 10, being releasably retained by the strap 18 when the case is opened.

What is claimed is:

In a kit of the kind described, a case including swingably connected cavity sections, the cavities in said sections being opened on the separation of the sections and closed on the bringing together of the latter, a pair of straps secured within one cavity and disposed transversely thereof, a polisher having a block-like back provided with a padded polishing medium extending with the back and terminating remote from the ends thereof for the separable engagement of the ends of said back by the said straps in abutting relation to the pad for holding the said polisher removably fitted within the cavity having the straps and against displacement therein, said back being provided with a recess having an opening in a side of said back in position to form with a wall of said cavity, a closed chamber for retention of a shoe shining accessory.
